(57) **CLAIM**

The ornamental design for a tripod camera mount, as shown and described.

DESCRIPTION

This application is a *broadening reissue* of U.S. Pat. No. D. 852,874, which granted from U.S. application Ser. No. 29/648,880, filed on May 24, 2018, which is a continuation of U.S. application Ser. No. 29/596,331, filed on Mar. 7, 2017, now U.S. Pat. No. D. 822,092, the entire [disclosure] disclosures of which [is] are incorporated by reference herein.

FIG. 1 is a [front, top, and right] *rear, bottom and left* perspective view of a tripod camera mount *showing the new design*;

FIG. 2 is [a rear, bottom, and left perspective] *front elevation* view thereof;

FIG. 3 is a [front] *rear elevation* view thereof;

FIG. 4 is a [rear] *left side elevation* view thereof;

FIG. 5 is a [left] *right side elevation* view thereof;

FIG. 6 is a [right] *top plan* view thereof; and,

FIG. 7 is a [top] *bottom plan* view thereof; and,

FIG. 8 is a bottom view thereof].

The ornamental design which is claimed is shown in solid lines in the drawings. The broken lines in the drawings form no part of the claimed design. Broken lines formed by equal length dashes (i.e., dash-dash) show unclaimed subject matter. Broken lines form by unequal length dashes (i.e., dash-dot) define bounds of the claimed design.

1 Claim, 15 Drawing Sheets

Matter enclosed in heavy brackets [ ] appears in the original patent but forms no part of this reissue; matter printed in italics indicates the additions made by reissue.
